FRANK NELSON, OF NEWKIRK, OKLAHOMA.

SPRING-LOCK KEY.

Application filed May 3, 1927. Serial No. 188,560.

This invention relates to a locking or cotter key for securing or locking a nut in position on a bolt, or for use in slotted bolts where nuts are not employed.

5 The primary object of the present invention is to provide a cotter key of such a character that the same will immediately lock itself in position upon being extended through a slot of a bolt without further attention.

10 Another object of the present invention is to provide an automatically locking cotter wherein disconnection can be readily accomplished without the employment of tools of any character.

15 The invention broadly contemplates the provision of an elongated member having one end enlarged to form a stop, said member being provided with a longitudinally extending passage in which a spring tongue is secured, a portion of the tongue being extended upwardly to engage against the wall of a bolt when the body has been extended through a slot therein, with one end of the tongue projecting a substantial distance beyond the end of the body to set up a releasing key, the outstanding portion of the spring tongue being disengaged from the bolt wall upon pressing downwardly upon the said key.

20 25 30 Another object of the present invention is to provide a locking cotter key of the character described which will be of simple but strong and durable construction, and easy to insert or remove from position.

35 Numerous other objects and advantages of the present invention will become apparent as the description of the same proceeds and the invention will be best understood from a consideration of the following detailed description taken in connection with the accompanying drawing forming a part of this specification, with the understanding, however, that the invention is not confined to any strict conformity with the showing of the drawing but may be changed or modified so long as such changes or modifications mark no material departure from the salient features of the invention as expressed in the appended claims.

40 45 50 In the drawing:

Figure 1 shows a bolt in side elevation having threaded upon one end thereof a castle nut and showing the key embodying the present invention in position thereon.

55 Figure 2 is a central longitudinal section

of the threaded end of the bolt shown in Figure 1, showing the interior construction of the cotter key associated therewith.

Figure 3 is a detailed perspective view of the cotter key embodying the present invention and.

Figure 4 shows a threadless bolt in side elevation showing the present cotter extended through a slot therein.

Referring now to the drawing in detail, 65 wherein like numerals of reference indicate corresponding parts throughout the several views, the numeral 1 in Figures 1 and 2, indicates a bolt body upon the end of the shank of which screw threads 2 are formed. 70 Threaded upon the bolt 1 is a castellated nut 3 and the body of the bolt has formed therethrough adjacent the free end thereof, the transverse passage 4 usually formed for the insertion of cotter keys of the present well-known construction, the usual key engaging between the castles of the nut 3 to maintain the same against turning, as is well understood.

75 The self locking cotter key embodying the present invention is indicated generally by the numeral 5, and as is clearly shown in Figure 2, this key comprises an elongated body formed of a pair of relatively narrow elongated flat bodies 6 arranged in closely spaced parallel relation and having an integral connecting portion 7 therebetween and extending throughout the length thereof along two adjacent edges. There is thus set up a body having a longitudinally extending 80 channel 8, open at each end and at the top as shown in Figure 3.

85 90 95 100 105 Each of the members 6 at one end of the body has extending from the edge thereof a member 9, which members, together, form a stop. Formed integral with the connecting portion 7 at one end of the same is an elongated spring tongue indicated generally by the numeral 10. This tongue adjacent the attached end thereof is inclined sharply upwardly and extends beyond the upper edges of the members 6 as shown in Figures 2 and 3 where it is then bent downwardly as indicated at 11, to a point slightly below the top edges of the members 6, after which it is turned and directed toward and beyond the opposite end of the body 5, being slightly inclined upwardly as shown. The free outer end of this tongue provides a manipulating means as indicated by the numeral 12 to 110

facilitate downward flexing of the tongue to cause the upper end of the sharply inclined forward portion to be depressed below the top edges of the members 6.

5 From the foregoing description, it will be readily seen that when the ends of the members 6 are directed through the passage 4 of the bolt when the body is forced therethrough, the spring tongue 10 will be depressed until the vertical portion 11 thereof passes through the passage 4 of the bolt whereupon the tongue will spring upwardly placing this forward portion 11 against the side wall of the bolt and thus preventing retraction of the cotter member. When in this position, the upstanding stops 9 will contact with the opposite side of the bolt body and it will thus be readily seen that the cotter is effectively held in the passage of the bolt, 20 against movement in either direction. It will be readily understood from the foregoing, that upon the depression of the free end 12 of the tongue, the vertical portion 11 will be retracted downwardly between the members 6 of the body and thus permit withdrawal of the cotter from the slots.

With reference to the showing of Figure 4, the bolt member 13 here shown is of threadless type wherein no nut is employed, this 30 bolt only being provided with a transverse passage through which a locking member or cotter is adapted to be extended. The present self locking cotter is readily adapted to be used in connection with this type of bolt 35 as well as with the type shown in Figures 1 and 2, and as there is no difference in the device used in the two types of bolts, the same numerals are used in connection with this figure as are used in connection with Figures 1, 2, and 3.

From the foregoing description, it will be readily understood that with a cotter key of, the herein described character, castellated nuts may be quickly secured in position against turning and the cotter key may be readily removed from position without the employment of the usual key opening tool, necessary in connection with the use of cotters of the character wherein two spring 50 legs are forced apart after being extended through the bolt slots.

Having thus described my invention, what I claim is:

1. A cotter of the character described, comprising an elongated body adapted to be extended through the transverse slot of a bolt and having a longitudinally extending recess formed therein, an upstanding stop body formed at one end of said first mentioned body, and a spring tongue formed within said recess and extending throughout the length of the recessed body and beyond one

end thereof, said tongue being formed to provide adjacent the other end of the recess body, a bolt engaging portion normally extending 65 from the recess and said extended end of the tongue constituting a manipulating means for retracting the projecting portion of a tongue into the recess.

2. A cotter of the character described, comprising an elongated body adapted to be extended through the transverse slot of a bolt and having a longitudinally extending recess formed therein, an upstanding stop body formed at one end of said first mentioned body, and a spring tongue formed within said recess and extending throughout the length of the recessed body and beyond one end thereof, said tongue being formed to provide adjacent the other end of the recess body, a bolt engaging portion normally extending 75 from the recess and said extended end of the tongue constituting a manipulating means for retracting the projecting portion of a tongue into the recess, said tongue having that end adjacent the projecting portion thereof formed integral with the recess body at the base of the recess.

3. A cotter key of the character described, comprising an elongated body formed of a pair of closely spaced flat parallel members having a connecting portion therebetween and extending throughout the edges thereof at one side of the body forming the opposite side of the body and the end open throughout, 90 upstanding stop members formed at one end of the body and an elongated spring tongue positioned between the parallel members of the body and having one end formed integral with the connecting portion, said tongue 95 at the attached end inclining sharply upwardly from said attached portion and extending a slight distance beyond the free edges of the side members, the remaining portion of the tongue being positioned between said side members and having the free end thereof extending beyond the end of the body to provide a manipulating means.

4. A cotter key of the character described, comprising a relatively long body of channel formation throughout, a spring tongue within the body and secured at one end thereto, the other end of the tongue projecting beyond one end of the body, a stop carried by and projecting from one longitudinal edge 115 of the body adjacent the end from which the spring tongue projects, and stop means carried by said tongue and in spaced relation to said first mentioned stop and normally projecting beyond the said longitudinal edge 120 of the body.

In testimony whereof I affix my signature.

FRANK NELSON.
